UNITED STATES PATENT OFFICE.

FRANCIS B. AGLAR, OF ST. LOUIS, MISSOURI, ASSIGNOR TO THE INTER-
CHANGEABLE BRAKE BEAM COMPANY, OF SAME PLACE.

BRAKE-BEAM.

SPECIFICATION forming part of Letters Patent No. 609,396, dated August 23, 1898.

Application filed June 22, 1896. Serial No. 596,453. (No model.)

To all whom it may concern:

Be it known that I, FRANCIS B. AGLAR, of the city of St. Louis, State of Missouri, have invented certain new and useful Improvements in Brake-Beams, of which the following is a full, clear, and exact description, reference being had to the accompanying drawings, forming a part hereof.

My invention relates to brake-beams; and it consists in the novel construction, combination, and arrangement of parts hereinafter shown, described, and claimed.

Figure 1 is a top plan view of my improved brake-beam. Fig. 2 is a side elevation of the compression member or back-strut, looking in the direction indicated by the arrows 2, the central portion of the member being broken away. Fig. 3 is an enlarged detail view of the ends of the brake-beam. Fig. 4 is a sectional view on the line 4 4 of Fig. 5. Fig. 5 is a vertical sectional view on the line 5 5 of Fig. 4. Fig. 6 is a horizontal sectional view on the line 6 6 of Fig. 4. Fig. 7 is a sectional detail showing the construction of the finger-guards and the means of attaching the same to the brake-beam. Fig. 8 is a front elevation in detail of the clip used in attaching the finger-guard to the compression member. Fig. 9 is a front elevation of the rigid hollow strut or king-post of which I make use. Fig. 10 is a detail sectional view on the line 10 10 of Fig. 9. Fig. 11 is a front elevation of the strut shown in Fig. 9. Fig. 12 is a sectional view on either of the lines 12 12 of Fig. 9. Fig. 13 is a top plan view of a nut-lock of which I make use. Fig. 14 is a longitudinal sectional view on the line 14 14 of Fig. 13. Fig. 15 is a side elevation of a key used in fastening the strut to the compression member. Fig. 16 is a transverse sectional view on the line 16 16 of Fig. 15.

In the construction of my improved brake-beam I make use of the compression member or back-strut 5, which is an open-seam tube made of rolled-steel plate. The tube thus constructed has the rectangular cut-away portion 6, the sides 7 of which are equidistant from a line extending from the open seam 8 of said tube. A cut-away portion 9 extends inwardly from the inner ends of the

cut-away portion 6, and said cut-away portions 9 are somewhat narrower than said cut-away portion 6 and have the inner rounded ends 10. The longitudinal centers of the cut-away portions 9 and 6 are on a line with the open seam 8. Upon each end of the compression member 5 is placed a reversible and interchangeable head 11. (Shown in detail in Figs. 4, 5, and 6.) The brake-heads 11 are constructed with both sides alike, and by this construction it is possible to make them all from one pattern.

Approximately in the vertical center of the brake-head and near the rear side thereof is a circular opening 12, designed to receive the end of the compression member 5. Projecting into the front side of said opening 12 are lugs 13 and 14, designed to fit within the rectangular cut-away portion 6 of the compression member. At each end of the opening 12 is a recess 15 in the sides of the brake-head and surrounding said opening, and said recesses are designed to receive drop-plates 16.

A short distance above the circular opening 12 is a circular opening 17, by means of which the brake-beams are connected to the hangers.

Between the lugs 13 and 14 is a semicircular depression 18, designed to receive the truss-rod 19, the ends of which are placed in the cut-away portions 9 of the compression member 5, the circular ends 10 of said cut-away portions fitting closely around said truss-rod. The drop-plates 16 are placed upon the extreme ends of the truss-rod 19 and against the sides of the brake-heads 11 and in the recesses 15. The nut-locks 20 are placed upon the ends of the truss-rod 19 against the outer faces of the drop-plates 16, and then the nuts 21 are screwed onto said truss-rod against said nut-locks.

The inner ends of the recesses 15 are substantially square, as shown in dotted lines in Fig. 4, and the drop-plates 16 fit closely within said recesses. The faces 22 of the drop-plates 16 are approximately at right angles to the truss-rod 19, while the inner faces 23 of said drop-plates are at right angles to the compression member 5. The faces 24 of said drop-plates intersect the faces 22 at approxi-

mately right angles and are flat and designed to receive the downwardly-turned ends 25 of the nut-locks 20.

- The portion of the opening 12 in the brake-head 11 which is designed to engage directly against the surface of the end of the compression member 5 consists of the three annular lugs 26, between which are the annular depressions 27. The opposite side of the opening 12 from the lugs 26 consists of the curved surface 28, which is concave in cross-section and from the center of which projects the lugs 13 and 14, and between said lugs is the depression 18, designed to receive the truss-rod.
- 15 The portion 29 of the brake-head 11, through which the opening 12 is formed, is substantially circular in cross-section, as shown in Fig. 4. Directly above the lug 13 is a second circular portion 30, through which is 20 formed the opening 17. The rib 31 projects upwardly from the portion 29 and surrounds the portion 30.

Walls 32 and 33 project inwardly in approximately parallel lines from the top and bottom, respectively, of the circular portion 29, and from the inner end of the wall 33 a curved body 34 projects upwardly and terminates in the end 35. The rib 31 is attached to the center and top side of the wall 33 and 30 to the rear side of the curved body 34 and the end 35. Projecting forwardly from the edges of the body 34 are flanges 36, designed to have the brake-shoe inserted between them.

Extending downwardly from the inner end 35 of the wall 32 is a curved body 37, substantially like the body 34 and terminating in the end 38, which is substantially like the end 35. Flanges 39 project forwardly from the edges of the body 37 and are substantially identical 40 in construction and purpose with the flanges 36. The inner faces of the ends 35 and 38 are concave, forming the recesses 40, designed to receive the brake-shoe. The space between the walls 32 and 33 is cored out, forming the 45 opening 41, the rearwardly-projecting lugs 42, and the inwardly-projecting lugs 43. The bodies 44 connect the bases of the lugs 42 and 43 with the inner ends of the walls 32 and 33, respectively, and projecting forwardly from 50 the bodies 44 are the lugs 45, designed to engage the brake-shoe.

The strut or king-post 46 is placed upon the center of the compression member or back-strut 5 and projects forwardly therefrom to 55 engage the center of the truss-rod 19. The details of the strut 46 are shown in Figs. 9, 10, 11, and 12. This strut is composed of malleable iron and is all made in one piece. The rear end of the strut has the aperture 47, de- 60 signed to receive the compression member 5. The aperture 47 is substantially circular in cross-section and communicates with the key-seat 48, designed to receive the key 49 for the purpose of holding the strut rigidly in position upon the compression member.

Projecting forwardly from the body 50, in

which the key-seat 48 is formed, is a circular body 51, which is cored out and made hollow, as shown in section in Fig. 12. Extending transversely of the front end of the body 51 is 70 a body 52, from the ends of which parallel bars 53 extend forwardly to a body 54, to which said bars are attached. The bars 53 are mates, as shown in section in Fig. 10. The outer surfaces of said bars are segments of a circle, 75 and the inner surfaces of said bars correspond with the shape of the outer surfaces, with the exception that strengthening-ribs 55 are inserted longitudinally of said inner surfaces. At approximately the center of said bars 53 are 80 circular bodies 56, extending through said bars, and said circular bodies have the alined apertures 57, designed to receive the pivot of the brake-lever. The bars 53 and the apertures 57 are set at an angle of approximately 85 forty-five degrees relative to a horizontal line.

Extending forwardly from the center of the body 54 is a circular body 58, which is cored out and made hollow, as shown in Fig. 12. Projecting upwardly from the front end of 90 said body 58 are the ears 59, having the horizontally-alined apertures 60. The lower end of the hanger may be positioned between the ears 59, and a bolt may pass through the apertures 60 and through said hanger.

Attached to the front end of the body 58 is a body 61, in the front face of which is the recess 62. The recess 62 is bounded by the parallel walls 63 and the curved concave wall 64, connecting said parallel walls, and is designed to receive the center of the truss-rod 19. In the center of the wall 64 is the opening 65, through which the core is removed.

The key 49 is shown in detail in Figs 15 and 16. Said key 49 is of considerable width and 105 is curved in cross-section to fit the outer surface of the compression member 5. In longitudinal section or elevation the key is slightly thinner at its point than near its head 66. This key is driven tightly into the recess 48, 110 and then its point 67 is upset to hold it firmly in position.

Finger-guards 68 are placed near the ends of the compression member 5 and inside of the brake-heads 11. The details of these 115 finger-guards and the means of connecting the same to the brake-beam are shown in Figs. 7 and 8.

A malleable-iron clip 69 is designed to fit around the compression member 5, and its 120 ends 70 and 71 project upwardly in parallel planes and a slight distance apart. A bead 72 extends from the base of the end 70 in a central position along the outer surface of the body of the clip to the base of the end 71. 125 In the center of the end 71 is a square opening 73, and in the center of the end 70 is a circular opening 74 in alinement with said square opening 73. Projecting inwardly from the upper edges of the ends 70 and 71 are the 130 lugs 75 in alinement with each other. A malleable-iron guard-hook 76 consists of the

vertical portion 77, having a square opening corresponding to the opening 73 and designed to be placed in alignment with said opening, with said vertical portion against the outer 5 face of the end 71 and the horizontal portion 78 attached to the lower end of said vertical portion and the hooked end 79 designed to engage the truss-rod 19.

The rod 80 has its rear end 81 reduced in 10 size and screw-threaded and designed to pass through the circular opening 74 in the end 70 of the clip. Immediately back of the screw-threaded end 81 upon said rod 80 is a portion 82, which is reduced in size and squared and 15 designed to fit within the square opening in the vertical portion 77 of the guard-hook 76 and to pass through the square opening 73 in the end 71. A nut-lock 83 is placed upon the screw-threaded end 81 and against the end 70, 20 and a screw-threaded nut 84 is placed upon said screw-threaded end 81 and against said nut-lock. The nut-locks 20 and 83 are shown in detail in Figs. 13 and 14. They are composed of malleable iron, and each nut-lock 25 consists of the body portion 85, having the centrally-located aperture 86, of a size suitable to fit the bolt upon which the nut-lock is to be used.

At one end of the body 85 is a portion 87, 30 joined to said body at right angles, and at the opposite end of said body 85 are the ends 88 and 89, between which is the cut-away portion 9. The portion 87 is designed to engage a suitable face upon the body through which 35 the bolt passes, and the ends 88 and 89 are designed to be turned up to engage the sides of the nut after it has been screwed into position.

By constructing the compression member 40 or back-strut 5 of open-seam tubing formed of steel plate I am enabled to get greater strength out of less weight of material than by the constructions heretofore in use. The brake-heads are of malleable iron and are 45 cored out and of such shape as to give the greatest possible strength with the least possible weight of material.

By the use of the drop-plates and the configuration of the brake-heads, as heretofore described, the brake-heads are made reversible and interchangeable, which is always a great advantage in any mechanical construction. By this means I am enabled to use the same 55 brake-head upon either end of the beam and upon either the front or back beam.

By the use of the hollow rigid king-post or strut I am enabled to get greater strength with less material than by the old construction. By the use of the wide curved key in 60 attaching the strut to the compression member I obtain a very rigid and efficient connection with the least possible expense, and by making the strut hollow and annealing it I get the greatest possible strength from the 65 least possible material.

In the construction of the finger-guards the hook engaging the truss-rod is of especial im-

portance, as it prevents the finger-guard from being driven inwardly upon the compression member. It also acts as a support for the 70 free end of the finger-guard.

The nut-lock which I employ possesses great 75 advantages over the use of two nuts or of the nut-locks heretofore used for this purpose.

I am aware that hollow brake-beams are not 80 new and that rigid struts or king-posts are not new and that compression members for such beams formed of open-seam rolled-steel-plate tubing are not broadly new, the latter being shown in a previous application of my 85 own and in other patents, and I am also aware that it is not new to employ in a brake-beam a longitudinally-slotted tubular compression member having the slot edges in apposition except at the points where the tension-rod enters the compression member; but I am not aware that a compression member 90 has been made as herein shown, described, and claimed, consisting of an open-seam tubing formed of rolled steel plate having the 95 edges of said open seam approximately in contact with each other substantially throughout the distance between the points near each end where the tension-rod enters the compression member and cut away from said 100 points to the end of said compression member in a manner to form open-ended slots at each end of said compression member for the reception of the tension-rod and a lug projecting from the brake-head, and this particular construction I have found in practice 105 to be very desirable, and therefore claim the same; nor am I aware that the other points of construction which I show, describe, and claim have been used previous to my invention of the same.

I claim—

1. In a brake-beam, a compression member 110 constructed of open-seam rolled-steel-plate tubing, and a rigid tubular malleable-iron strut securely keyed upon said compression member, substantially as specified.

2. In a brake-beam, a compression member 115 constructed of open-seam rolled-steel-plate tubing and a rigid tubular malleable-iron strut securely keyed upon said compression member, which strut consists of the rear end having the aperture 47 designed to receive 120 the compression member and having the key-seat 48 at one side of said aperture, the hollow circular body 51 attached to said rear end, the body 52 at the front end of said circular body, the parallel bars 53 extending 125 forwardly from said body 52, said parallel bars having the circular bodies 56 through 59 which are formed the aligned apertures 57, the body 54 attached to the front ends of said bars, the hollow circular body 58 projecting forwardly from said body 54, the ears 59 projecting upwardly from the front end of said 130 circular body 58 and having the horizontally-aligned apertures 60, the body 61 attached to the front end of said circular body 58 and having the recess 62 in its front face and de-

signed to receive the truss-rod, and the key 49 in the key-seat 48, substantially as specified.

3. In a brake-beam, the compression member constructed of open-seam rolled-steel-plate tubing, a rigid tubular malleable-iron strut securely keyed to said compression member, reversible and interchangeable brake-heads upon said compression member, drop-plates 10 upon said heads and a truss-rod connecting said heads and engaging said strut, substantially as specified.

4. In a brake-beam, a compression member constructed of open-seam rolled-steel-plate tubing, a rigid tubular malleable-iron strut securely keyed to said compression member, reversible and interchangeable brake-heads upon said compression member; which brake-heads consist of the portion 29 having the 15 opening 12, the circular portion 30 having the opening 17, the rib 31 projecting upwardly from the portion 29 and surrounding the portion 30, the walls 32 and 33 projecting inwardly from the top and bottom, respectively, of the 20 circular portion 29, the curved body 34 projecting upwardly from the inner end of the wall 33 and having the end 35, the rib 31 being attached to the top of the wall 33 and to the rear side of the curved body 34 and the 25 end 35, the flanges 36 projecting forwardly from the edges of the body 34, the curved body 37 extending downwardly from the inner end of the wall 32 and having the end 38, the flanges 39 projecting inwardly from the edges 30 of the body 37, the lugs 42 and 43 projecting into the opening 41 formed between the curved bodies 34 and 37, the bodies 44 connecting the bases of the lugs 42 and 43 with the inner ends of the walls 32 and 33, respectively, and the lugs 45 projecting forwardly from the bodies 44; drop-plates upon 35 said heads and a truss-rod connecting said heads and engaging said strut, substantially as specified.

45 5. In a brake-beam, a compression member constructed of open-seam rolled-steel-plate tubing and a rigid tubular malleable-iron strut securely keyed upon said compression member, reversible and interchangeable 50 brake-heads upon said compression member, drop-plates upon said brake-heads, a truss-rod connecting said heads and engaging said strut, the nut-locks 20 upon said truss-rod and against said drop-plates, nuts upon said truss-rod and against said nut-locks, said nut-locks 55 consisting of the body portions 85 having the centrally-located apertures 86, the portion 87 joined to said body 85 at right angles and the ends 88 and 89 joined to said body at the 60 opposite end from the portion 87, substantially as specified.

6. In a brake-beam, a compression member constructed of open-seam rolled-steel-plate tubing and a rigid tubular malleable-iron strut securely keyed upon said compression member, reversible and interchangeable 65 brake-heads upon said compression member,

drop-plates upon said brake-heads, a truss-rod connecting said heads and engaging said strut, nut-locks upon said truss-rod and against said drop-plates, nuts upon said truss-rod and against said nut-locks, and finger-guards attached to said compression member, each of which finger-guards consists of the malleable-iron clip 69 designed to fit upon said 70 compression member, the ends 70 and 71 projecting upwardly from said clip, the lug 75 projecting inwardly from the upper edges of said ends 70 and 71, the malleable-iron guard-hook 76 having one end against the end 71 80 and its other end engaging the truss-rod, the rod 80 having the screw-threaded end 81 and the squared portion 82 designed to fit in the openings in said ends 70 and 71, the nut-lock 83 upon said screw-threaded end and the nut 85 84 upon said screw-threaded end and against said nut-lock, substantially as specified.

7. A brake-beam comprising a compression member or back-strut, which compression member is constructed of open-seam rolled-steel-plate tubing, a rigid tubular malleable-iron king-post or strut securely keyed upon said compression member, finger-guards attached to said compression member, reversible and interchangeable brake-heads upon 95 said compression member, drop-plates upon said brake-heads, a truss-rod connecting said brake-heads and engaging said strut, and hooks attached to said finger-guards and engaging said truss-rod, substantially as specified.

8. In a brake-beam, a compression member or back-strut 5 constructed of open-seam rolled-steel-plate tubing and having the rectangular cut-away portion 6 in each of its ends 10 and the cut-away portions 9 extending inwardly from said cut-away portion and having the rounded inner ends 10, substantially as specified.

9. In a brake-beam, a reversible and interchangeable head 11 consisting of the portion 29 through which is formed the opening 12, the lugs 13 and 14 projecting into said opening 12 and forming the semicircular depression 18 between said lugs, said portion 29 being constructed to form the recesses 15 surrounding said opening 12 and designed to receive drop-plates, the circular portion 30 through which is formed the opening 17, the rib 31 projecting upwardly from the portion 29 and surrounding the portion 30, the walls 32 and 33 projecting inwardly from the top and bottom of said circular portion 29, the curved body 34 projecting upwardly from the inner end of the portion 29 and having the end 35, the flanges 36 projecting forwardly from the edges of the body 34, the curved body 37 projecting downwardly from the inner end of the wall 32 and having the end 38, the flanges 39 projecting outwardly from the edges of the body 37, lugs 42 and 43 projecting into the opening 41 formed between the walls 32 and 33, the bodies 44 connecting the bases of the lugs 42 and 43 with the inner ends 11

of the walls 32 and 33 and the lugs 45 projecting forwardly from the bodies 44, all cast in one piece and annealed, substantially as specified.

5 10. In a brake-beam, the rigid tubular strut or king-post 46 consisting of the rear end having the aperture 47 designed to receive the compression member and the key-seat 48 communicating with said aperture 47 and designed to receive the key 49, the hollow circular body 51 attached to said rear end, the body 52 attached to the front end of said circular body, the parallel bars 53 extending forwardly from the ends of said body 52, the circular bodies 56 having the apertures 57 at the centers of said parallel bars, the body 54 attached to the front ends of said parallel bars, the hollow circular body 58 extending forwardly from said body 54, the ears 59 extending forwardly from the front end of said hollow circular body 58, the body 61 attached to the front end of said hollow circular body 58 and having the recess 62 in its front face, said recess being designed to receive the truss-rod, all cast in one piece and annealed, substantially as specified.

11. In a brake-beam, the finger-guards 68, each of which consists of the malleable-iron clip 69 designed to fit around the compression member, the ends 70 and 71 projecting upwardly from said clip, said ends 71 having the square opening 73 and the end 70 having the circular opening 74 in alignment with said square opening, the lugs 75 projecting inwardly from the upper edges of the ends 70 and 71, the malleable-iron guard-hook 76 consisting of the vertical portion 77 having the squared opening corresponding to the opening 73 and designed to be placed in alignment with said opening and against the outer face of the end 71, the horizontal portion 78 attached to the lower end of said vertical portion and the hooked end 79 designed to engage the truss-rod, the rod 80 having the screw-threaded end 81 designed to pass through the circular opening 74 and the squared portion 82 designed to pass through the squared openings in the vertical portion 77 and the end 71, the nut-lock 83 upon the screw-threaded end 81 of said rod and against the end 70 and the screw-threaded nut 84 upon said screw-threaded end and against said nut-lock, substantially as specified.

12. A brake-beam comprising the compression member or back-strut 5 constructed of open-seam rolled-steel-plate tubing, the malleable-iron reversible and interchangeable heads 11, the drop-plates 16 designed to engage said heads, the truss-rod 19 connecting said heads, the nut-locks 20 upon the ends of said truss-rod, the nuts 21 upon the ends of said truss-rod and against said nut-locks, the rigid malleable-iron strut or king-post 46 upon said compression member and engaging said truss-rod, the key 49 interposed between said compression member and said strut and having its point 67 upset to hold it rigidly in po-

sition, the finger-guard 68 attached to said compression member and having the hooked ends 79 engaging said truss-rod, substantially as specified.

13. In a trussed metallic brake-beam, a compression member constructed of open-seam rolled-steel-plate tubing, the edges of the open seam of said tubing being approximately in contact with each other substantially throughout the distance between the points near each end where the tension-rod enters the compression member, and cut away from said points to the ends of said compression member in a manner to form open-ended slots at each end of said compression member.

14. In a trussed metallic brake-beam, a compression member constructed of open-seam rolled-steel-plate tubing, the edges of the open seam of said tubing being approximately in contact with each other substantially throughout the distance between the points near each end where the tension-rod enters the compression member, and cut away from said points to the extreme ends of said compression member in a manner to form open-ended slots for the reception of the said tension-rod and also for the reception of lugs from the brake-heads.

15. In a trussed metallic brake-beam, a compression member constructed of open-seam rolled-steel-plate tubing, the edges of the open seam of said tubing being approximately in contact with each other substantially throughout the distance between the points near each end of said tube where the tension-rod enters the compression member, and cut away at the said points where the tension-rod enters the compression member to form slots for the reception of said tension-rod, and also cut away outside of said points and extending to the extreme ends of said compression member so as to form open-ended slots for the reception of lugs from the brake-heads, the last-mentioned slots being wider than the first-mentioned slots so as to form shoulders at the junctions of the first and second above-mentioned slots, said shoulders being adapted to engage the said lugs from the brake-heads and prevent the latter from sliding toward the king-post of the beam.

16. In a brake-beam, a compression member constructed of open-seam rolled-steel-plate tubing having the rectangular cut-away portion 6 at each of its ends, and a narrower cut-away portion extending inwardly from said cut-away portion 6.

17. In a trussed metallic brake-beam, the combination of a strut or king-post, a tension-rod, brake-heads having lugs projecting into the compression member, and a tubular compression member formed with open-ended notches at its ends for the passage of the said tension-rod and the said lugs from the brake-heads, said notches being formed with a transverse shoulder adapted to engage with said lugs, with suitable means of tying the several said members of the beam together.

18. In a brake-beam with a tension-rod and a compression member, a clip provided with lips, a bolt passing through said lips and serving the double purpose of a finger-guard and a bolt for clamping said clip on or around the compression member, and a hook engaging with and hooking over said tension-rod mounted at its base upon one of the lips of said clip and held in place by said bolt, with a nut upon the end of said bolt.
19. A strut or fulcrum-support for a brake-beam cast in the form of a circular tube cored

throughout its entire length and formed with internal strengthening-ribs and a transverse circular recess at one end for the reception of a tubular compression member, and with a longitudinal slot between the two ends for the reception of the brake-lever.

I testimony whereof I affix my signature in presence of two witnesses.

FRANCIS B. AGLAR.
